(57) **CLAIM**

The ornamental design for a snack box as shown and described.

DESCRIPTION

FIG. 1 is a front, bottom, and left perspective view of the snack box showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, top, and right perspective view thereof; and, FIG. 9 is a perspective view of the snack box in an open state.

The broken lines shown in the drawings represent portions of the snack box that form no part of the claimed design.
